DISPENSING RECEPTACLE

Henry Hermani, Baltimore, Md., assignor to The Tin Decorating Company of Baltimore, Baltimore, Md., a corporation of New Jersey

Application October 27, 1932. Serial No. 639,917

6 Claims. (Cl. 221—108)

My invention relates to dispensing receptacles such as canisters adapted to contain granular or pulverized materials, and to be conveniently mounted so that the contents can be readily dispensed in predetermined quantities by simple operation.

The principal purpose of the invention is to provide a canister of the above type which may be cheaply manufactured from stamped metal parts easily assembled and joined to form the complete dispensing canister without employing extraneous or collateral fastening means or elements to hold the parts together.

All of the objects and advantages of the invention will become apparent and will be specifically referred to hereinafter during the course of the following detailed description of the accompanying drawing, which shows a preferred embodiment of the invention, and wherein Fig. 1 is a perspective view of a canister embodying my invention;

Fig. 2 is a vertical sectional view through the canister along the lines 2—2 of Fig. 3;

Fig. 3 is a view taken on line 3—3 of Fig. 2, with parts broken away; and

Fig. 4 is an exploded perspective view of the dispensing parts.

Referring to the drawing, the numeral 5 designates the tubular body of the canister which is preferably made of thin metal capable of being stamped and provided adjacent its top with a bead 6. The upper end of the body 5 is closed by a removable lid 7 which fits over the open end of the body with its lower edge adapted to contact the bead 6 to effect a substantially air tight closure. To the lower end of the tubular body 5, there is secured a tapering or flaring annular member 8 which is attached to the lower end of the body 5 by the crimped seam 9. The lower end of the annular member 8 is attached to a disc 10 by the crimped seam 11, and in the same seam the upper end of an annular band 12 is also crimped as indicated at 13. Thus, the disc 10, flaring member 8, and band 12, are united by a single seaming operation.

As is clearly shown in Figs. 3 and 4, the disc 10 has two openings 14 and 15 formed at spaced intervals at similar distances from the center of the disc 10. The disc also has formed centrally therein a smaller opening 16.

In order to effect dispensing of material from the canister, I provide a drum-like casing designated generally by the numeral 17 in Fig. 4 and adapted to fit within the band 12. All of the parts thus far described are formed by stamping from thin sheet metal, and the drum 17 is also preferably formed in the same manner by providing a plain band 18 and flanged caps 19 and 20 to fit over the top and bottom of the band. The greatest diameter of the drum 17 is slightly less

than the diameter of the disc 10 beneath which the drum is positioned with the cap 19 in contact with the disc 10 when the drum is inserted within the band 12. The drum 17 is also provided with openings 21 and 21' spaced apart substantially the same distance as the openings 14 and 15 on the disc 10. These openings 21 and 21' may be provided in accordance with my invention by forming the caps 19 and 20 with flanges 22 at the openings to engage with tubes 23 extending between the caps. The drum 17 is maintained within the band 12 by the flanged closure 24, the flange of which fits around the lower edge of the band 12. The closure 24 is provided with an opening 25 of substantially the same diameter as the openings 14, 15, 21, and 21'.

The band 12 is provided with a slot 26 through which is mounted a handle 27 attached at its inner end rigidly to the drum 17 to rotate the drum between the disc 10 and closure 24 a distance determined by the length of the slot 26, the ends of which constitute stops to movements of the handle. It should be apparent from the description thus far given, that the purpose of the two tubular openings 21 in the drum 17 is to collect material through the openings 14 and 15 and to alternately dispense the material thus collected through the opening 25 in the closure 24, as will be presently described in detail. It will be understood that the capacity of the openings 21 determines the amount of material dispensed therefrom.

In order to facilitate the dispensing of the material, and in accordance with the objects of my invention looking to the provision of the canister entirely from stamped parts, I may provide a scraper or agitator 27' in the nature of a metal strip bent upon itself and provided on its lower side with tangs 28 which are inserted through the opening 16 in disc 10 and received in slots 29 in the top 19 of the drum. Thus when the drum is rotated, the agitator 27 will be rotated around the lower end of the canister above the disc 10 and within the limits of the tapering lower walls formed by the member 8. The ends of the agitator 27' may be beveled as at 30 to fit against the inner face of the member 8.

It is preferable to provide in connection with the canister, means for securing the same in a convenient position for use, and to this end I have shown a hooked member 31 attached to the canister as by rivets 32. This hooked member 31 may be engaged with a mating part, not shown, but of known type, so that the canister will be firmly supported for use.

In assembling the parts the body 5 is seamed to the member 8 and the latter is seamed to both the band 12 and disc 10 as shown in Fig. 2. The drum 17 is then inserted within the band 12 until the cap 19 contacts with the undersurface

of the disc 10. The handle 27 is inserted through the slot 26 and attached to the drum 17 at a point which, when the handle is at one extreme end of the slot 26, will place the opening 21' in registry with the opening 14 in the disc. This places the opening 21 under a solid portion of the disc 10 to be closed thereby at its top but in such position that when the handle is moved to the opposite end of the slot 26 the opening 21' will be moved into registry with the opening 15, while the opening 21' is simultaneously moved from registry with the opening 14. Of course, the closure 24 is applied to the lower end of the band 12 with the opening 25 at such a position that movement of the handle 26 to partly rotate the drum 17 will alternately bring the openings 21 and 21' into registry with the opening 25. This arrangement is best shown in Fig. 3. If the agitator or scraper 27 is to be used it is inserted through the open top of the body 5 and the tangs 28 are inserted through the slots 29, which may be so arranged on the cap 19 relative to the openings 21 and 21' that each complete movement of the drum will pass the scraper entirely across the openings 14 and 15 respectively.

From the foregoing, it should be obvious that with the parts in the position shown in Fig. 3, that when the handle 27 is moved to the right or in counter-clockwise direction that the drum 17 will be partially rotated, whereby the opening 21 will be moved from the dotted line position into registry with the opening 15 whereby the contents of the canister may flow down into the opening 21 and fill the same as the surface of the closure 24 is closing the bottom of the opening 21 after it has been moved to the stated position. With the parts in the position shown in Fig. 3, the opening 21' is in registry with the opening 14 and is filled or being filled while the opening 21 is in registry with the opening 25 and is discharging or has discharged its contents.

Under the construction and arrangement shown and described, it is possible to provide a dispensing canister which has a two-way operation to alternately discharge predetermined quantities of material and which can be made cheaply, due to the simple manner in which the parts are constructed, arranged, and joined. The canister can be refilled from time to time simply by removing the lid 7 and pouring in the material to be used. Obviously, since each movement of the drum to bring one of the openings therein into discharging relation with the opening 25 cuts off communication of that opening with the interior of the canister and establishes the other opening in the drum in communication with the interior of the canister but closed at its bottom by the closure 24, there is no likelihood of spilling the contents when refilling.

60 I claim:

1. A dispensing receptacle comprising a sheet metal container having lower walls inclined toward its axis, a plate across the lower end of said inclined walls, an annular sheet metal band below said plate, said plate, inclined walls and annular band being united by a single seam, said plate having a pair of openings, a dispensing member comprising a drum-like member mounted for rotation within said annular band below said plate and having formed therethrough a pair of openings, a closure for the lower end of said annular band having a discharge opening, the openings in said drum-like member being positioned for alternate registry with the openings in the plate and the opening in the closure,

and means for oscillating said plate within said band in opposite directions to bring said openings in the drum-like member into alternate registry with said other openings.

2. The structure of claim 1 wherein the drum-like member comprises a sheet metal band having top and bottom flanged closures, and tubular members mounted between said closures in communication with openings therein.

3. A dispensing receptacle comprising a container made of sheet metal, a tapered sheet metal band joined to the lower end of the container walls by seaming, a plate across the lower end of said band and having an opening communicating to the interior of the receptacle, an annular sheet metal band below said plate and tapered band, both of said bands and said plate being united by a single seam, a dispensing member mounted for partial rotation in said annular band below said plate, and a closure for the lower end of said annular band and having a discharge opening.

4. In a dispensing receptacle comprising a container made of sheet metal, a tapered sheet metal band joined to the lower end of the container by seaming, a plate across the lower end of said tapered band and having a pair of openings communicating into the interior of the receptacle, an annular sheet metal band below said plate and tapered band, both of said bands and said plate being united by a single seam, a drum-like member within the annular band below the plate and having a pair of openings adapted to alternately register with the openings in the plate, means for oscillating the drum-like member in opposite directions to bring said openings alternately into registry, and a closure for the lower end of said annular band having a discharge opening adapted to register with one of the openings in the drum-like member when the other of said openings is in registry with one of the openings in the plate.

5. A device for dispensing predetermined quantities of material from containers to which it is attached comprising a plate at the lower end of the container having two openings in communication with the interior of the container, an annular band below said plate, a drum-like member within said annular band and having a pair of openings between its top and bottom to register alternately with the openings in the plate, a closure for the lower end of the annular band having a discharge opening therein, a slot in the annular band, a handle extending through said slot and connected to the drum-like member, the parts being so associated that when the handle is abutting one end of the slot one of the openings in the drum-like member is covered by a portion of said plate and is in registry with the opening in the closure and the other opening in the drum-like member is in registry with one of the openings in the plate to collect the material from the container, and when the handle is in engagement with the other end of the slot said first opening in the drum-like member is in registry with the other opening in the plate and the second opening in the drum-like member is covered by a solid portion of the plate and is in registry with the opening in the closure.

6. The structure of claim 4 wherein an agitator is disposed across the lower end of the container with its ends adjacent the inclined walls and is connected through the plate with the drum for movement therewith.
